United States Patent Office

Des. 216,585
Patented Feb. 17, 1970

216,585

CONTAINER FOR A BOTTLE OR THE LIKE

Jay Doblin, Chicago, Ill., assignor to The Gillette Company, Boston, Mass., a corporation of Delaware

Filed Aug. 27, 1968, Ser. No. 13,287

Term of patent 14 years

Int. Cl. D9—04

U.S. Cl. D9—176

FIG. 1

FIG. 3

FIG. 1 is a view in side elevation of a container for a bottle or the like showing my new design; and FIG. 2 is a top plan view; and FIG. 3 is a view in vertical section. I claim: The ornamental design for a container for a bottle or the like, as shown.
